UNITED STATES PATENT OFFICE.

MICHAEL J. SASGEN, OF CHICAGO, ILLINOIS, ASSIGNOR TO GRAND SPECIALTIES COMPANY, OF CHICAGO, ILLINOIS, A CORPORATION OF ILLINOIS.

DOORSTOP.

Application filed September 11, 1922. Serial No. 587,333.

To all whom it may concern:

Be it known that I, MICHAEL J. SASGEN, a citizen of the United States, and resident of Chicago, in the county of Cook and State 5 of Illinois, have invented certain new and useful Improvements in a Doorstop, of which the following is a specification.

My invention relates to improvements in door stops and has special reference to a 10 stop adapted to prevent a door from being opened beyond a predetermined point.

The door stop of my invention belongs to the strut rather than the plunger class and the object of my invention is to provide a 15 strut-like door stop which shall be efficient in its action, in which the strut lever shall be capable of being lifted from its operative position without the necessity of stooping down to engage the lever, and which device 20 shall be provided with means for retaining the strut in inoperative position.

As my improved stop is adapted to interior use upon highly finished doors, I have arranged simple means for preventing the 25 strut from swinging against the door and possibly marring it when swung to its inoperative position.

A further feature of my invention relates to simple means for covering the pivoted 30 floor engaging end of the lever with a suitable rubber covering and also for encasing in rubber, the projections which are adapted to be engaged by the foot of the operator when lifting the lever from operative position.

My invention will be more readily understood by reference to the accompanying drawings forming part of this specification, and in which:—

40 Figure 1 is an elevational view of the device shown in full lines in operative position on a door, the swinging strut shown in inoperative position in dotted lines;

45 Figure 2 is a side elevation of the device as shown in Figure 1;

Figure 3 is a fragmentary vertical section on the line 3—3 of Figure 2;

50 Figure 4 is a fragmentary side elevation of the lower end of the strut, the rubber casing being shown in section;

Figure 5 is a horizontal sectional view on the line 5—5 of Figure 2;

55 Figure 6 is a detail section on the line 6—6 of Figure 1 showing a modified form of strut stop; and

Figure 7 is a similar view showing another modified form of strut stop.

In said drawings, 1 represents a vertical, swinging door upon which the device is adapted to be mounted. The device comprises a sheet metal bracket 2 consisting of an elongated base plate 3 having lateral projections 4 adjacent to its upper end perforated for receiving fastening screws 5 and the lower end 6 of the base being perforated 60 for receiving a fastening screw 7. Between its ends the bracket is provided with two upturned ears 8 which are adapted to project out at right angles to the base and are spread apart to receive one end of a swinging strut 65 9 between them. The strut is fastened between the ears 8 by a riveted pivot 10. The bracket is placed upon the door 1 at such a height that when the strut is swung down it will contact with the floor when in a position inclined upwardly and inwardly toward the door so as to brace the door against movement in one direction. 70 75

The upper end of the base is provided with two lateral projections 11 which are formed 80 up at right angles to the base, their outer ends 12 being arranged parallel with each other and spaced apart to receive the strut 9 between them when swung to vertical upstanding position. The projections 11 have 85 sufficient resiliency and are so related that when the strut is pushed between them they engage the strut with sufficient pressure to hold it in its vertical position.

At the lower end of the strut I provide a 90 shoe 13 preferably formed up from sheet metal to provide a relatively wide base 14 and lugs 15, the two lugs being adapted to straddle the lower end of the strut 9 and adapted to be pivotally mounted on the 95 lower end of the strut by a riveted pivot 16.

The upper ends of the lugs 15 are provided with extensions 17 bent to project laterally to form lifting lugs so that when it is desired to lift the strut from operative position it can be freed from the floor by the use of the toe of the shoe of the operator and when freed from the floor can readily be swung to inoperative position by the foot. The shoe 13 has a slight pivotal movement to 100 allow it to engage the floor with sufficient holding pressure without sliding, the pivotal movement being limited by the extreme lower end 18 of the strut which, as shown in Figure 2 in dotted lines, engages the bottom 110

plate 19 of the shoe 13 and prevents it swinging beyond a limited extent.

To provide friction between the shoe and the floor I preferably cover the shoe with a rubber envelope 20 forming the lower surface of the envelope into blunt transverse teeth 21 and curving the lower surface slightly in the direction in which the shoe swings, this for the purpose of obtaining good contact with the floor. I preferably make the envelope 20 to fit around the lower part or base of the shoe and provide it with an opening 22 in its top by which it can be readily placed in position on the shoe, the resiliency of the envelope and the tapered shape of the lower part of the shoe serving to retain the envelope in position once it has been placed thereon. In some instances I prefer to vulcanize the envelope 20 in position on the shoe.

To prevent the marring of the shoe of the operator by the projections when lifting the strut, I preferably cover the projections 17 with rubber envelopes 23 which may be retained upon said projections in any suitable manner such as vulcanizing them in position.

To prevent the marring of the door by the strut when raised to inoperative position I provide means on the base to prevent the contacting of the shoe or the strut with the door. This means as illustrated in the drawings preferably consists of a projection 24 preferably integral with the base and arranged to contact with the strut between its ends when swung to inoperative position. This projection as shown is struck up out of the base in the base forming operation being consequently easily and cheaply produced. Under some conditions of use it is desirable to have a cushioning stop for the strut as it is raised to inoperative position and for this purpose I may either cover the stop 24 with a rubber envelope 25 or I may provide a solid rubber stop 26 secured in some suitable manner to the base plate 2 such as by means of a screw 27.

I do not herein specifically claim the rounded or curved bottom surface of the shoe such being claimed in my companion application Serial Number 534,287.

As many modifications of my invention will readily suggest themselves to one skilled in the art, I do not limit or confine my invention to the specific details of construction herein shown and described.

I claim:

1. In a door stop, a vertically swinging lever for engagement with the floor to brace the door, a pivoted shoe on the free end of the lever, a rubber envelope on the shoe, the shoe having a lateral projection for convenience in lifting the strut, and said projection on the shoe covered with a yielding

material, as and for the purpose specified. 65

2. In a door stop, a base adapted to be secured to a door, a strut pivotally mounted on the base and adapted to engage the floor, a shoe pivotally mounted on the free end of the strut, means on the base above the pivotal connection of the strut therewith for yieldingly holding the strut in vertical inoperative position, and a projection rigid with the base for contact with the strut to prevent the strut contacting with the door when the strut is raised to inoperative position. 70 75

3. In a door stop, a base adapted to be secured to a door, a strut pivotally mounted on the base and adapted to engage the floor, a shoe pivotally mounted on the free end of the strut, means on the base above the pivotal connection of the strut therewith for yieldingly holding the strut in vertical inoperative position, and a cushioned projection rigid with the base for contact with the strut to prevent the strut contacting with the door when the strut is raised to inoperative position. 80 85

4. In a device of the kind described, a strut, means for pivotally mounting the strut at one end for swinging movement, a shoe secured to the free end of the strut, the shoe encased in rubber or the like. 90

5. In a device of the kind described, a strut, means for pivotally mounting the strut at one end for swinging movement, a shoe secured to the free end of the strut, the shoe provided with transversely extending V-shaped ribs. 95 100

6. In a device of the kind described, a strut, means for pivotally mounting the strut at one end for swinging movement, a shoe secured to the free end of the strut, the shoe provided with transversely extending 105 slightly yielding V-shaped ribs.

7. In a device of the kind described, a strut, means for pivotally mounting the strut at one end for swinging movement, a shoe secured to the free end of the strut, the shoe encased in rubber or the like and provided with transversely extending V-shaped ribs. 110

8. In a device of the kind described, a strut, means for pivotally mounting the strut at one end for swinging movement, a foot piece pivotally mounted on the free end of the strut, the foot piece encased in rubber or the like. 115

9. In a device of the kind described, a sheet metal base, two pairs of struck-up lugs on the base one above the other, a flat metal bar strut pivoted at one end between the lower pair of lugs to swing edgewise up and down, the upper pair of lugs formed to grip the wide side faces of the strut with frictional pressure to hold it in raised position. 120 125

10. In a device of the kind described, a sheet metal base, two pairs of struck-up lugs one above the other, the base formed with oppositely projecting securing ears 5 between the two pairs of struck-up lugs, a flat metal bar strut pivoted at one end between the lower pair of lugs to swing edge- wise up and down, the upper pair of lugs formed to grip the wide side faces of the strut with frictional pressure to hold it in 10 raised position.

Signed at Chicago, Illinois, this fifth day of September, 1922.

MICHAEL J. SASGEN.
